UNITED STATES PATENT OFFICE.

JOHN SHAYLOR, OF LINDENWOLD, NEW JERSEY.

CENTER FINDER AND PUNCH.

1,378,287.

Specification of Letters Patent. Patented May 17, 1921.

Application filed August 29, 1917. Serial No. 188,786.

To all whom it may concern:

Be it known that I, JOHN SHAYLOR, a citizen of the United States, residing at Lindenwold, in the county of Camden and 5 State of New Jersey, have invented certain new and useful Improvements in Center Finders and Punches; and I do hereby declare the following to be a full, clear, and exact description of the invention, such as 10 will enable others skilled in the art to which it appertains to make and use the same.

This invention relates to a center finder and punch, and the primary object of the 15 invention is to provide a punch especially adapted for finding and marking the centers of shafts.

Another object of the invention is the provision of means for automatically bringing 20 the punch directly in the center of the shaft, so that the punch can be actuated so as to accurately mark the center of the shaft in a comparatively short time.

A further object of the invention is the 25 provision of a hollow frusto-conical member carrying a sliding punch on its upper end, the frusto-conical member forming a guide for the work, so that the punch will automatically be positioned in the exact center 30 of the work.

A still further object of the invention is the provision of an adjustable guide carried by the lower portion of the frusto-conical member for engaging the work and 35 holding the same in position in the frusto-conical member, while the sliding punch is being actuated.

A still further object of the invention is the provision of means for moving the sliding 40 punch downward into engagement with the work after the center has been found, so that the same can be forcibly brought into engagement with the work to mark the center on the shaft.

45 A still further object of the invention is the provision of a center finder and punch of the above character, which is durable and efficient in use, one that is simple and easy to manufacture and one that can be 50 placed upon the market at a reasonable price.

With these and other objects in view the invention consists in the novel construction, arrangement and formation of parts, 55 as will be hereinafter more specifically described, claimed and illustrated in the ac-

companying drawings, forming a part thereof, in which—

Figure 1 is a vertical section taken through the improved center finder and 60 punch, and

Fig. 2 is a section taken on the line 2—2 of Fig. 1.

Referring to the drawings in detail, wherein similar reference numerals designate corresponding parts throughout the several views, the numeral 1 generally indicates the improved center finder and punch, which includes a hollow frusto-conical member 2 having a tubular housing 3 70 formed on its upper surface as at 4. A punch 5 is slidably mounted in the tubular housing and consists of a cylindrical shank having its lower end tapered to provide a point 6. An outwardly extending guide 75 flange 7 is formed on the shank of the punch 5 and an expansion coil spring 8 bears against the same and on the lower inwardly extending guide flange 9 formed on the inner surface of the tubular housing 3 and the spring 8 normally holds the punch 5 in a raised position. The upper end of the tubular housing 3 is externally threaded as at 10 and receives an internally threaded cap 11, which closes the upper end 85 of the tubular housing. The cap 11 is provided with a central opening 12 through which the upper end of the shank of the punch protrudes and the cap forms a guide 90 for the punch 5.

An outwardly extending ear 13 is formed on the lower edge of the frusto-conical member 2 and supports a guide 14. The guide 14 includes a horizontally extending arm 15 and a downwardly extending right 95 angularly positioned arm 16 which is adapted to bear against the work after the same has been placed in the frusto-conical member 2.

A diagonal brace arm 17 extends from one 100 arm to the other and forms a rigid structure. The horizontal arm 15 is provided with a slot 18 through which extends the set screw 19. The set screw 19 extends through an aperture in the ear 13 and a winged nut 20 105 is fitted on the end of the set screw and by loosening or tightening the set screw 19 the guide 14 can be moved inwardly or outwardly.

The tubular housing 3 is provided with 110 a vertical guide slot 21 through which extends the actuating pin 22. The pin 22 is

threaded into the shank of the punch 5 and by moving the same, the punch can be brought downward into engagement with the work against the tension of the spring 8.

5 In operation of the improved center finder and punch, the work which may be either a square or round shaft is positioned in the frusto-conical member which will guide the same upward and position the punch 5 directly over the center of the shaft. The guide 14 is then moved into engagement with the work and the winged nut 20 is tightened to hold the guide arm in engagement with the work and the pin 22 is then 15 moved downwardly so as to position the punch in engagement with the work and then the punch is struck with a hammer or the like so as to mark the center on the shaft.

20 In practice, I have found that the form of my invention, illustrated in the accompanying drawings and referred to in the above description, as the preferred embodiment, is the most efficient and practical; yet 25 realizing the conditions concurrent with the adoption of my device will necessarily vary,

I desire to emphasize the fact that various minor changes in details of construction, proportion and arrangement of parts may be resorted to, when required, without sacrificing any of the advantages of my invention as set forth.

What is claimed is:—

A centering device of the character specified, comprising a punch having an outer 35 annular flange, a tubular housing slidably receiving the punch and having an inner annular flange engaging the punch, and provided at its lower end with a flared 40 guide member, a cap grooved in its lower 45 side to receive the upper end of the housing and centrally apertured to receive the punch, and an expansion spring encompassing the punch and confined between the annular flanges of the housing and punch.

In testimony whereof I affix my signature in presence of two witnesses.

JOHN SHAYLOR
